United States Patent Office

Des. 193,893
Patented Oct. 23, 1962

193,893

HEATING PAD CONTROL OR SIMILAR ARTICLE

Frank M. Grunwald, Syracuse, N.Y., assignor to General
Electric Company, a corporation of New York

Filed Mar. 6, 1962, Ser. No. 69,105

Term of patent 14 years

(Cl. D26—13)

Fig. 1

Fig. 2.

Fig. 3.

FIG. 1 is a perspective view of the heating pad control or similar article embodying my new design;

FIG. 2 is a top plan view of the heating pad control shown in FIG. 1; and

FIG. 3 is a side elevational view of the heating pad control shown in FIG. 1.

I claim:

The ornamental design for a heating pad control or similar article, substantially as shown.
